UNITED STATES PATENT OFFICE.

ALFRED W. BRUCE, OF NEW YORK, N. Y.

LOCOMOTIVE-BOILER SUPPORT.

Application filed December 8, 1926. Serial No. 153,309.

My invention more particularly relates to a multiplex boiler support for locomotives of the "Mallet" type, and has for an object to provide a supporting structure, in which the stresses imposed on a plurality of connections between the saddles and the boiler, will be efficiently distributed to the connections for the several saddles, thus obviating the localization of stresses of undesirable magnitude, on the connections of any of the saddles.

The improvement claimed is hereinafter fully set forth.

The "Mallet," or articulated type locomotive, comprises front and rear frames, pivoted together to enable the front engine frame to swivel in the manner of a leading truck, when traversing curved track, and to return to normal longitudinal alignment when traversing tangent track. The cylinders of a high pressure engine are mounted on the rear frame, and the cylinders of a low pressure engine are mounted on the front frame. It has been the usual practice to secure the boiler by studs passing through its shell, to independent saddles, one of which is bolted to the cylinder castings on the rear frame, and the others of which, are slidably mounted on bearing plates, supported on crossties connecting the side members of the front frame. A serious objection to this form of construction is that the stresses encountered in service are not distributed efficiently to the studs of all of the saddles, but are localized on the studs of particular saddles, with the result that stresses of sufficient magnitude to produce steam leaks between the studs and boiler shell, are frequently imposed on certain of the studs.

In the present invention, the saddles of the front and rear engine frames, are rigidly connected together, and held against longitudinal displacement by longitudinally extending members, so that stresses, which, in the construction heretofore known, would be localized on the studs of one of the saddles, will be efficiently distributed between the studs of all of the saddles, thus reducing to a minimum the possibility of leaks. The improvement effects a material economy, as the replacement of studs or bolts is a costly operation, often necessitating the removal of the boiler flues, and the consequent keeping

of the locomotive out of service for long periods of time.

In the accompanying drawings: Figure 1 is a diagrammatic side view, in elevation, of the forward portion of a locomotive embodying my invention; Fig. 2, a top plan view of the multiplex boiler support; Fig. 3, a central longitudinal section of the construction shown in Fig. 2, a portion of the lower part of the boiler being shown in dotted lines; Fig. 4, a transverse section on the line *a-a* of Fig. 3; Fig. 5, a transverse section on the line *b-b* of Fig. 3; and Fig. 6, a view in perspective of the multiplex boiler support.

In the practice of my invention, referring descriptively to the specific embodiment thereof which is herein exemplified, as applied in a four cylinder articulated locomotive, having a rear frame, 10, and an independent front frame, 11, each of which is of bar type, comprising an upper and a lower rail, and is provided with pedestals in which the journal boxes of the driving wheels, 12, are mounted in the usual manner. The frames are pivotally coupled together by a king pin fitting in sockets in extensions on the rear and front frames, the construction permitting swiveling movements of the front frame from its normal position in line longitudinally with the boiler, in passing from a tangent to a curve of the track, and into said normal position in passing from a curve to a tangent; and the maintenance of the front frame in normal position while the locomotive is traversing tangent or straight portions of the track.

A pair of cylinders, 13, is mounted on the forward end of the rear frame, and a pair of cylinders, 14, is mounted on the forward end of the front frame.

The forward end of the boiler, 15, is mounted on a multiplex support, comprising a rear frame boiler saddle, 16, and front frame boiler saddles, 16^a and 16^b. Each of the saddles has a substantially box-shape base, 17, to which is secured a flange, 18, having an upper face curved in correspondence with the curvature of the boiler shell. Holes, 19, are formed in the flanges, 18, for the reception of suitable studs or bolts, which connect the boiler to the saddles. The three saddles are rigidly fastened together

and secured against longitudinal movements, by a pair of longitudinally extending members, 20, each having a top and a bottom, horizontal outwardly presented, flange, 5 21, and, 22, respectively.

The front and the rear wall of each saddle base, 17, is formed at its bottom with an outwardly presented horizontal flange, 23, and the end walls of the bases, 17, of the 10 saddles, are each provided with an opening, 24, for the passage of a centering rod, not shown. All of the saddles and their connecting members, are preferably formed together as a one piece cast structure, but it is 15 within the contemplation of the invention to form the parts separately, any suitable fastening means being employed to secure them together.

The rear frame saddle, 16, is rigidly secured to the cylinder casting, 13, by bolts 20 passing through suitable holes, in the flanges, 22, and, 23, of the multiplex support.

In order to permit the necessary lateral movement of the front end of the boiler and 25 its saddles, with relation to the front frame, the saddles, 16^a, and, 16^b, are slidably mounted on bearing plates, 25, carried by supports, 26; extending transversely from side to side of the front frame.

30 From the foregoing description, it will be apparent that the multiplex boiler support will insure efficient distribution of the stresses encountered in service, to the studs or bolts of each of the saddles, thus obviating the liability present in structures heretofore known, of stresses of sufficient magnitude to produce leaks, being localized on the studs or bolts of one of the saddles.

I claim as my invention and desire to secure by Letters Patent:

40 1. A multiplex support for locomotive boilers, formed as an integral casting, and comprising a plurality of boiler saddles, and means for maintaining said saddles in longitudinally spaced relation.

45 2. A multiplex support for locomotive boilers, comprising a rear frame boiler saddle, a front frame boiler saddle, and means, independent of the boiler, for maintaining said saddles in longitudinally spaced relation.

3. A multiplex support for locomotive boilers, formed as an integral casting, and comprising a rear frame boiler saddle, a 55 front frame boiler saddle, and means for maintaining said saddles in longitudinally spaced relation.

40 4. A multiplex support for locomotive boilers, comprising a rear frame boiler saddle, a plurality of front frame boiler saddles, and means, independent of the boiler, for maintaining said saddles in longitudinally spaced relation.

5. A multiplex support for locomotive

boilers, formed as an integral casting, and 65 comprising a rear frame boiler saddle, a plurality of front frame boiler saddles, and means for maintaining said saddles in longitudinally spaced relation.

6. A multiplex support for locomotive 70 boilers, formed as an integral casting, and comprising a plurality of boiler saddles, and a longitudinally flanged member for maintaining said saddles in longitudinally spaced 75 relation.

7. A multiplex support for locomotive 80 boilers, comprising a rear frame boiler saddle, a front frame boiler saddle, and a longitudinally flanged member for maintaining said saddles in longitudinally spaced 85 relation.

8. A multiplex support for locomotive 90 boilers, formed as an integral casting, and comprising a plurality of boiler saddles, each embodying a base having a front, rear, and two end walls, and a flange supported 95 on the base and formed with an upper surface curved in correspondence with the boiler and adapted to support the same; and means for maintaining said saddles in longitudinally spaced relation.

9. A multiplex support for locomotive 100 boilers, comprising a plurality of boiler saddles, each embodying, a base, having two end walls, formed with an opening for a centering rod, and a rear and a front wall; and a flange supported on the base, and formed with an upper surface curved in correspondence with the boiler, and adapted to support the same; and a longitudinally 105 flanged member, independent of the boiler, for maintaining the saddles in longitudinally spaced relation.

10. In a locomotive, the combination of 110 two independent frames coupled for relative swivelling movement, a boiler saddle rigidly secured to one of the frames, a boiler saddle slidably mounted on the other frame for transverse movements relative thereto, and means, independent of the boiler, for maintaining the saddles in longitudinally spaced relation.

11. In a locomotive of the articulated type, the combination of a boiler; two independent frames for supporting the boiler, coupled for relative swivelling movement; a cylinder casting rigidly secured to one of the frames; a boiler saddle rigidly mounted on said casting; a boiler saddle slidably mounted on the other frame for transverse movement relative thereto; means for fastening each of the saddles to the boiler; and means, independent of the boiler and directly connected to each of the saddles, for distributing stresses encountered in service, to the fastening means of each of the saddles.

ALFRED W. BRUCE.
